UNITED STATES PATENT OFFICE

103,717

DESIGN FOR A VEGETABLE BIN OR SIMILAR ARTICLE

William B. Flanagan, Brooklyn, N. Y., assignor to A. Kreamer, Incorporated, Brooklyn, N. Y.

Application February 3, 1937, Serial No. 67,413

Term of patent 14 years

To all whom it may concern:

Be it known that I, William B. Flanagan, a citizen of the United States, residing at Brooklyn, New York, county of Kings, and State of New York, have invented a new, original, and ornamental Design for a Vegetable Bin, or Similar Article, of which the following is a specification, reference being had to the accompanying drawing forming a part thereof.

Figure 1 is a perspective view of a vegetable bin, showing my new design, with the doors and cover in open position.

I claim:

The ornamental design for a vegetable bin, or similar article, as shown.

WILLIAM B. FLANAGAN.
